Primary Examiner — Martie K Holtje*(74) Attorney, Agent, or Firm* — Boyle Fredrickson, S.C.**CLAIM**

The ornamental design for an enclosure for a timer, as shown and described.

DESCRIPTION

FIG. 1 is a right front isometric view of an enclosure for a timer showing our new design;

FIG. 2 is a left front isometric view thereof;

FIG. 3 is a left rear isometric view thereof;

FIG. 4 is a right rear isometric view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a right side elevational view thereof; and,

FIG. 10 is a left side elevational view thereof.

The structural features depicted by broken lines in the drawings have been shown for the purpose of illustrating portions of the enclosure for a timer that form no part of the claimed design.
